UNITED STATES PATENT OFFICE.

CHESTER A. SNOW, JR., OF WASHINGTON, DISTRICT OF COLUMBIA.

AEROPLANE CONTROL.

1,419,419.

Specification of Letters Patent. Patented June 13, 1922.

Application filed October 13, 1921. Serial No. 507,408.

To all whom it may concern:

Be it known that I, CHESTER A. SNOW, Jr., a citizen of the United States, residing at Washington, in the District of Columbia, 5 have invented a new and useful Aeroplane Control, of which the following is a specification.

This invention relates to an aeroplane control designed primarily for use in facilitating the landing of an aeroplane so as to retard the speed of the machine as it approaches the landing point without disturbing its longitudinal stability.

A further object is to combine with the retarding means a means for anchoring the machine during the starting of the motor and until the pilot is ready to take off.

It is a fact well known to those skilled in the art that practically 80% of all aeroplane accidents are strictly landing accidents. When a pilot undertakes to effect a landing he must first maneuver for position, with regard to the lay of the land and direction of the wind, and then come down in a glide 25 sufficiently steep to insure against loss of flying speed to keep the machine from stalling. The pilot, when safely above the edge of the field and only a few feet from the ground "flattens out" or gradually 30 comes out of the glide and, by lifting the nose of the machine, assumes a line of flight approximately parallel to the ground. The pilot then coasts along just a few inches off the ground, bringing the nose of the machine 35 higher and the tail lower to accurately counteract the tendency of the machine to settle to the ground, and as the machine loses more and more of its flying speed and as the nose points farther into the air the 40 crucial movement in the landing operation comes nearer. Under some conditions a landing can be effected with comparative ease and safety but in many cases a machine is compelled to land in a cross wind which 45 causes the machine to drift sideways with the result that a wheel is torn off or the landing chassis is buckled and the machine caused to turn over. At other times the machine is compelled to contact with a bump 50 or ridge or other obstruction causing it to bounce or jump into the air and unless the control is skillfully maintained the machine, having lost its flying speed, will fall sideways and be injured as hereinbefore described.

It is an object of the present invention to

provide the machine with a supplemental plane located below and in advance of the center of gravity of the machine, this supplemental plane being adjustable angularly 60 without disturbing the longitudinal stability of the machine, to retard the speed of the machine and thus greatly reduce the probability of accidents occurring while effecting a landing.

Another object is to provide a plane useful as a supplemental lifting plane for changing altitude, and as a means for regulating the speed of the machine while in flight for the purpose of taking photographs, dropping 70 bombs on selected targets, and maintaining position in squadron formations where there are differences in types of machines, their speeds, their plane alignments, and the loads carried thereby.

Another disadvantage present in aeroplane structures is the difficulty experienced in holding them properly anchored after the engines have been started and before the pilots have assumed their positions at the 80 controls.

Heretofore when alone in open country it has often been necessary for the pilot to place a chock in the form of a stone, a small log or the like in front of each wheel of the 85 running gear and to then start the engine. Thereafter it has been necessary to crawl up to the chocks and dangerously near the rotating propeller to remove the chocks to free the machine for forward movement.

It is an object of the present invention to combine anchoring means with the supplemental plane herein described so that the pilot, by shifting the plane to a negative angle of incidence can bring the anchoring 95 means into contact with the surface of the ground and from which position said anchoring means can be removed at will by the pilot without leaving his seat.

Another object is to have the supplemental 100 plane so located that the blast from the rotating propeller will maintain the anchoring means in operative relation with the ground in spite of the lifting action exerted to a limited extent by the air blast against 105 the main or sustaining plane of the machine while said machine is anchored.

A further object is to provide a supplemental plane which can be utilized to prevent the machine from turning over if 110 forced down on the surface of a body of water.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a side elevation of an aeroplane having the present improvements combined therewith, said view being partly in diagram and showing lines of force set up while the machine is in flight.

Figure 2 is a rear perspective view of the control and the front portion of the aeroplane, the supplemental plane being shown in one of the positions in which it may be adjusted while the machine is in flight.

Figure 3 is a front perspective view of the front portion of the machine, the supplemental plane being positioned to anchor the machine before the beginning of the flight.

Figure 4 is a view showing in diagram the relative positions of the parts while the machine is anchored.

Figure 5 is a similar view showing the relative positions of the parts while the machine is making a landing.

Referring to the figures by characters of reference 1 designates an aeroplane structure of any desired type provided with the usual main or sustaining planes 2, the tail plane 3 and the tractor propeller 4. The struts 5 of the running gear are movably engaged, as ordinarily, by the transverse axle 6 on which are mounted the wheels 7. The axle and struts have relative up and down movement and cushions 8 of rubber extend over the axle 6 so as to retard the upward movement of the axle relative to the struts and thus absorb shocks due to landing.

The construction thus far described can be found on standard types of aeroplanes and constitutes in itself no part of the present invention. As is well known the axle of the running gear of an aeroplane is disposed below and in advance of the center of gravity of the machine and this location is taken advantage of in the present instance by providing a streamline axle or, in other words, by mounting on or forming with the axle a supplemental plane 9 mounted for angular adjustment whereby its angle of incidence may be varied at will. The means for controlling this plane can consist of a lever 10 connected to and adapted to swing back and forth with the plane, the connection between the lever and the plane being such, however, as to allow a lateral tilting

and vertical play of the plane without correspondingly moving the control lever. In the present instance this action is permitted by forking the lower end of the lever 10 as shown at 11 and placing it astride an enlarged flattened portion of the axle. The lever can be locked in any position to which it may be adjusted angularly, any desired form of locking means being used, such for example as a toothed segment 13 and a pawl 14.

Extending from the leading edge of the supplemental plane 9 are spurs 15 adapted, when the plane is tilted to a negative angle of incidence as in Figures 3 and 4, to contact with the surface on which the wheels 7 are resting. Skids 16 may be arranged under the trailing portion of the plane at the sides thereof to facilitate landings.

As indicated by the diagram, Figure 1, the supplemental plane 9 is so positioned below and in front of the center of gravity of the machine that the lines of force resultant from the drift and lift due to the speed of the machine and the angle of incidence of the plane, will at all times extend either through or in advance of the center of gravity. In Figure 1 the plane has been shown elevated to its greatest angle and the line of force resulting from the lift and drift are shown extending through the center of gravity. Obviously, however, any downward variation or adjustment of the plane from the extreme position shown in Figure 1 will result in a forward movement of the lines of force so that the center of gravity would be in rear thereof. Thus it will be seen that when the supplemental plane 9 is in use as a sustaining plane under normal conditions there will be no tendency on the part of this plane to trip the machine onto its nose or cause it to dive as would be the case should the plane be so located that the resultant lines of force due to the lift would extend back of the center of gravity.

It will be understood that by mounting the plane on the axle or making it a part of the axle it will not only reduce the air resistance of the axle to forward movement by streamlining it but will also when in normal flight and adjusted approximately parallel to the main plane, give a large additional lift.

In landing the plane 9 should be turned up to a high angle of incidence. This will produce greatly increased lift as well as drift components, thus causing the supplemental plane to hold the machine in the air a few moments longer as well as to offer greatly increased air resistance to its forward motion. It might first appear that this resistance so far below the center of gravity would have a tendency to cause a dangerous tripping effect but as has heretofore been explained and as illustrated in Figure 1 such

action will be counteracted by the lift which will be exerted at a point in advance of the center of gravity. Thus with increased lift combined with increased resistance to 5 forward motion, a slower and safer landing may be made than has heretofore been possible.

When a forced landing on water is unavoidable, by giving the plane 9 a high angle of incidence it will act as a hydroplane 10 step, causing the machine to glide along the

surface of the water at first instead of digging in and possibly violently overturning the machine on first contact with the water.

15 During the landing of the machine the skids 16 can be brought into play so as to contact with the surface of the ground. In the drawings these skids have been shown as separate parts below the rear portion of 20 the plane 9 but I do not wish to restrict myself to this arrangement because if desired the trailing edge portion of the plane could itself be so designed as to constitute a skid.

25 When it is desired to start the motor the plane is adjusted to a negative angle of incidence as shown in Figures 3 and 4 and locked with the ends of the spurs 15 in contact with the ground. At this time those

30 portions of the tires on the wheels 7 contacting with the ground are flattened more or less because of the weight of the machine supported by the tires. Therefore, when the propeller is set in motion the blast of 35 air created will act on the main wings or planes to exert a lifting action sufficient to relieve the tires of considerable weight and, consequently, under normal conditions the spurs would be lifted out of contact with

40 the ground a greater or less distance, depending upon the force exerted and the amount of distortion or compression of the tires. In the present instance, however, the same air blast will be directed against the 45 plane 9 so as to force it downwardly and maintain the tires under compression. As

the cushioning means 8 have been relieved to a certain extent by the lifting action exerted against the wings or planes 2, the 50 resultant loss of weight upon the axle will be partly compensated for by the downward movement of the plane 9 under the action of the air blast, thus maintaining the compression of the tires. Consequently the spurs

55 will be maintained in close proximity to the surface of the ground so that during the forward movement of the machine resulting from the thrust of the propeller the spurs will be caused to dig into the ground and 60 thus hold the machine against further movement in a forward direction until, by the actuation of lever 10, the plane 9 is swung to disengage the spurs from the ground. As the plane 9 is located under the planes 2 it 65 will be subjected not only to the force of

the direct blast from the propeller but also to the reaction of air downwardly and rearwardly from the planes 2.

While the improvements herein described are designed primarily for use on aeroplane 70 structures it is to be understood that many of them can be employed to advantage in connection with airships of the lighter than air type and by the term "aeroplane" it is not intended to restrict this invention to a 75 machine of any particular type.

What is claimed is:—

1. In an aeroplane a manually, angularly adjustable streamline running gear axle. 80 2. In an aeroplane an angularly adjustable streamline running gear axle having its axis of rotation substantially fixed relative to the aeroplane structure.

3. In an aeroplane a streamline running gear axle held against bodily movement relative to the aeroplane structure and adjustable 85 angularly while so held.

4. In an aeroplane a fixed running gear and an angularly adjustable streamline axle carried thereby. 90

5. In an aeroplane a fixed running gear and an angularly adjustable streamline axle carried thereby below and in advance of the center of gravity.

6. The combination with an aeroplane, of 95 a streamline running gear axle below and in advance of the center of gravity of the machine and adjustable angularly, said axle being so located that the line of force resultant from the drift and lift will extend under 100 normal operating conditions through or in advance of the center of gravity, thereby to maintain undisturbed the longitudinal equilibrium of the machine.

7. In an aeroplane structure an angularly 105 adjustable streamline running gear axle below and in advance of the center of gravity, a control lever connected to and extending from said axle, and means for securing the lever and axle in any position to which they 110 may be adjusted angularly.

8. In an aeroplane a running gear having an angularly adjustable streamline axle below and in advance of the center of gravity of the machine, and means for securing said 115 axle in any position to which it may be adjusted angularly.

9. The combination with an aeroplane structure, of a supplemental plane below and in advance of the center of gravity, anchoring means upon the front portion of said plane, and means for adjusting the plane angularly to any positive angle of incidence without disturbing the longitudinal equilibrium of the machine while in flight, and 120 for adjusting said plane to a negative angle of incidence to position the anchoring means for engagement with the ground. 125

10. In an aeroplane structure a supplemental plane below and in advance of the 130

center of gravity of the structure, anchoring means upon the front portion of the plane, a skid at the rear portion of the plane, and means for adjusting said plane to any positive angle of incidence to bring the skid to landing position and to hold the plane so that the line of force resultant from the drift and lift will at all times extend through or in advance of the center of gravity, said plane being adjustable to a negative angle of incidence to position the anchoring means for engagement with the ground.

11. The combination with an aeroplane structure including a running gear having supporting wheels with resilient tires, an axle, and yieldable cushioning means engaging the axle, of a supplemental plane below and in advance of the center of gravity of the machine and adjustable angularly to a negative angle of incidence thereby to receive the force of the air blast set up by the propeller of the machine, an anchoring means upon the plane for engagement with the ground and adapted to be maintained in such engagement by the action of the air blast upon the plane.

12. In an aeroplane the combination with a running gear including supporting wheels having yielding tires, an axle, and cushioning means engaging the axle, of a supplemental plane, anchoring means on the front portion thereof, and means for adjusting said plane

angularly to position the anchoring means in engagement with the ground while the wheels are supporting the weight of the machine, 35 said plane being adapted to be pressed downwardly by the air blast from the propeller during the starting of the machine, thereby to maintain the anchoring means in contact with the ground while the said wheels are 40 relieved of the weight of the machine due to the lifting action of the air blast upon the main planes of the machine.

13. In an aeroplane structure a landing gear including an axle mounted for up and 45 down movement relative to the structure, wheels on the axle having compressible tires, an angularly adjustable plane below and in advance of the center of gravity of the aeroplane structure, and ground engaging 50 anchoring means carried thereby, said plane being adjustable to a negative angle of incidence whereby the blast from the propeller will exert a forward movement to the structure and depress the adjustable plane to compress the wheel tires and force the anchoring means into the ground.

In testimony that I claim the foregoing as my own, I have hereto affixed my signature in the presence of two witnesses.
